UNITED STATES PATENT OFFICE.

ALBERT K. ELROD, OF HUCKABAY, TEXAS, ASSIGNEE OF ONE-HALF TO WILLIAM E. DEATON, OF R. F. D. NO. 1, HUCKABAY, TEXAS.

SLIDE-SCRAPER.

1,246,074.

Specification of Letters Patent. Patented Nov. 13, 1917.

Application filed April 23, 1917. Serial No. 163,895.

To all whom it may concern:

Be it known that ALBERT K. ELROD, a citizen of the United States of America, residing at Huckabay, in the county of Erath 5 and State of Texas, has invented certain new and useful Improvements in Slide-Scrapers, of which the following is a specification.

The present invention relates to improvements in slide scrapers particularly adapted for use in building roads, surface tanks, and other excavating or building work wherein such a device is needed. The primary object of the invention is the provision of an 10 efficient scraper or excavating device which may be loaded quickly and dumped with equal facility, and which may be manipulated in the operations of dumping, loading, and lifting in a simple manner, thus enabling the operator to devote his attention to the work and to the draft horse. The invention consists essentially in certain novel 15 combinations and arrangements of parts as hereinafter more fully specified and as disclosed in the drawings.

In the accompanying drawings I have illustrated one complete example of the physical embodiment of my invention constructed according to the best mode I have 20 so far devised for the practical application of the principles of my invention.

Figure 1 is a top plan view of a scraper embodying my invention.

Fig. 2 is a side elevation of the scraper.

Fig. 3 is a front view of the device.

Fig. 4 is a vertical sectional view of the scraper, with some parts omitted for convenience of illustration.

The scraper is adapted to be drawn along 40 over the ground by a horse, and is therefore provided with rather broad, metallic runners as 1 and 2, made up of any suitable shapes of iron, as are also the two upper longitudinal bars 3 and 4 forming with the 45 lower bars, the frame of the device. At the front the upper and lower frame bars are brought together and connected by a cross brace 5, a similar brace 6 being located at the rear, and the intermediate transverse brace 50 7 completes the cross braces. Two pairs of upright braces are utilized, as 8 at the rear, and the special form of braces 9 and 9' located approximately midway of the longitudinal frame bars. Other and suitable

braces may be utilized where required to 55 provide a rigid and durable frame, and a driver's seat 10 is provided at the rear, the seat post 11 being adjustable in the cross bar 6 in usual manner. At the front of the frame is located the clevis 12 to which the 60 draft horse or other power may be applied to drag the frame over the ground on its runners 1 and 2.

The scoop or shovel 13 is supported in the frame, or rather suspended in the frame 65 from the arch bar 14, extending transversely of the frame and having its ends 15 and 16 passed through apertured brackets 17 and 18 secured against the inner surfaces of the opposite side walls of the scoop or shovel. 70 Through the medium of a rock bar 19 the shovel may be raised or lowered. This rock bar is journaled in bearings 20 at the sides of the frame and has a pair of fixed arms 21 21' spaced apart and pivoted at 22 to the arch bar 19. By means of the lever 23, of usual construction, the bar may be rocked and through the pivoted arms the arch bar may be lifted and with it the shovel, the two 75 trunnions 15 and 16 being guided in vertical 80 movement in the slots 24 24' in the uprights 9 9'. It will be seen also that the trunnions in their slotted posts, receive the pressure of the load as the shovel is dragged over the ground in the operation of loading, and prevent 85 displacement of the shovel. By means of the hand lever 23 the shovel may be lifted to its maximum altitude and held there, when out of operative position, as when the scraper is being transported. In addition to 90 the manual lifting device, the shovel may also be lifted by the foot or pedal bar 25 which is U-shape having its side arms pivoted at 26 26' to the loose links 25' (one at each side of the frame) and these links are 95 each pivoted, as at 26' to a fixed, downwardly projecting bracket arm 27. The ends of the U-shaped pedal bar are formed with eyes 28, 28 through which the respective trunnions 15 and 16 pass, and it will readily 100 be seen that by bearing down on the bar 25 the shovel may be lifted from the ground, the fulcrum points being located at 26 26'. Thus, after the shovel is loaded, the operator 105 may reach down with his foot, press down on the bar and lift the loaded shovel from the ground so that the device may be transported to the dump. The dumping or un-

loading of the shovel is accomplished through the instrumentality of the hand lever 28' which is pivoted at 29 on the arch bar 14, the lever device of course being bodily movable with the vertically movable arch bar. A link 30 is pivoted to the lever 28' and at 30' has a loose sleeve surrounding the shovel bar 31 which extends across the upper edge of the shovel at its rear with fixed 5 brackets 32 32 connecting bar and shovel, and in Fig. 1 it will be seen that the ends of the bar are attached to the shovel at 33, 33, thus holding the shovel bar rigid with the shovel at all times. It will thus readily be 10 seen that by lifting the lever 28' (Fig. 2) and turning it to the front, the shovel will be lifted at the rear and turned forward, thus dumping the contents therefrom, quickly and completely and the shovel is 15 then turned down by lowering the lever 28'. It is evident that the two operations may be accomplished with facility and despatch through the instrumentality of the manual or pedal levers for lifting the loaded shovel, 20 and through the lever 28' for dumping the load from the shovel. The apparatus is of course utilized in characteristic manner for doing its work, and it is believed that from the above description and an inspection of 25 30 the accompanying drawings it will be evident I have provided a comparatively per-

fect device for accomplishing the desired results.

What I claim is:

1. The combination with a supporting 35 frame including oppositely disposed slotted posts, an arch bar vertically movable in the posts and a shovel oscillatably suspended near its front on the bar, a rock bar journaled in the frame and means for rocking the bar, 40 and rocker arms loosely connecting said arch bar and rock bar, of a shovel bar fixed at the rear upper end of the shovel, a lever pivotally supported on the arch bar, and a pivoted link connecting said lever and shovel 45 bar as described.

2. The combination with a slidable frame comprising opposite side members and transverse connecting bars and slotted posts, of an arch bar with end trunnions in the 50 slotted posts, an oscillatable shovel having a front suspension on said trunnions, a rock bar and rock arms connected to said arch bar and an operating lever for said rock bar whereby the shovel may be elevated, a shovel 55 bar fixed at the rear upper end of the shovel, a lever pivotally supported on the arch bar, and a pivoted link connecting said lever and shovel bar whereby the shovel may be dumped.

In testimony whereof I affix my signature.
ALBERT K. ELROD.

Copies of this patent may be obtained for five cents each, by addressing the "Commissioner of Patents, Washington, D. C."
